UNITED STATES PATENT OFFICE

RICHARD E. MEAD, OF QUEENS VILLAGE, NEW YORK, ASSIGNEE TO MERGENTHALER LINOTYPE COMPANY, A CORPORATION OF NEW YORK

TYPOGRAPHICAL MACHINE

Application filed July 21, 1931. Serial No. 552,129.

This invention relates to typographical machines, such as linotype machines of the general organization represented in Letters Patent of the United States to O. Mergenthaler, No. 436,532, wherein matrices, stored end to end in a channeled magazine, are released therefrom by suitably actuated escapement devices and then composed side by side in line. After composition, the matrix line is transferred to the face of a slotted mold, the mold filled with molten metal to form a slug or linotype against the matrices which produce the type characters thereon, and the matrices thereafter returned by a distributing mechanism to the magazine from which they started.

The magazines as now used in the commercial linotype machines (especially those of full size), being made largely of brass, are quite heavy and difficult to handle in their application to and removal from the machine, imposing a rather severe burden upon the operator in carrying the magazines back and forth between the machine and their place of storage. Not only that, the operator is liable to drop the magazines in handling and thus cause serious damage to the magazines themselves or to other parts of the machine.

The present invention aims to facilitate the handling of the magazines by materially reducing the weight thereof, and with these and other objects in view, the invention consists of a magazine structure in which the top and bottom plates are formed of an alloy of aluminum. The particular alloy employed is peculiarly adapted for use in a magazine structure possessing not only the desired lightness, but in addition many other necessary characteristics, such as sufficient stiffness to prevent distortion, sufficient hardness to resist the wear of the matrices in passing through the guiding channels, and the capability of being readily machined in the formation of the matrix guiding channels.

45 In the accompanying drawing:

Fig. 1 is a top plan view of a magazine constructed in accordance with the present invention, the upper plate being broken away to expose the interior construction;

50 Fig. 2 is an enlarged longitudinal broken

section through the magazine taken on the line 2—2 of Fig. 1; and

Fig. 3 is an enlarged transverse cross section taken on the line 3—3 of Fig. 2.

In the preferred embodiment illustrated, 55 the magazine structure (of the so-called "Model 5" type), consists of a top side plate 1, a bottom side plate 2, and longitudinally extending side bars 3, the space between the side plates thus being closed at the opposite 60 edges of the magazine but open at the opposite ends thereof to permit the passage of the matrices therethrough, in a manner familiar to those skilled in the art.

On their inner faces, the side plates 1 and 2 are formed with opposed longitudinally extending grooves 4, wherein the customary projecting ears of the matrices engage and whereby the matrices are guided in their passage through the magazine. On its underside, the lower plate 2 is provided with a number of cross bars, one 5 near the upper end of the magazine, one 6 near the lower end thereof, and three intermediate ones 7, 8 and 9, which several bars are fastened to the magazine structure by means of bolts 10 passing through the upper plate 1, the side bars 3, the lower plate 2, and the cross bars themselves (see Fig. 1). The cross bar 9 is extended at its opposite ends beyond the side 75 edges of the magazine to serve as a support for the magazine in applying it to or removing it from the machine, all as well understood in the art. A longitudinal central bar 11 is 80 fixed to the transverse bars to aid in guiding the magazine to and from its seat in the machine.

At its lower extremity, the magazine structure has fixed to it upper and lower cross bars 12 and 13 for the mounting of a matrix locking device and the matrix releasing escapements, but such devices are not illustrated herein, since they form no part of the present invention.

In accordance with the present invention, the top and bottom side plates 1 and 2 of the magazine are made (instead of brass or steel as heretofore) of an aluminum alloy possessing characteristics which peculiarly adapt it 95 for use in a magazine structure. After trials 100

of many different aluminum alloys, it has been found that an alloy consisting of the following ingredients is best suited for the purpose:

	Percent
5 Aluminum	94.4
Copper	4
Silicon	.5
Manganese	.5
10 Magnesium	.6
	100

The top and bottom magazine plates constructed of this particular aluminum alloy possess the necessary stiffness to prevent distortion; are hard enough to resist wear from the matrices in passing therethrough, and in practice have been found to remain free from the formation of a black gummy substance which frequently results from the friction of brass (of which the matrices are composed) on aluminum. Moreover, plates constructed of such alloy are readily machineable, i. e., the grooved channels for the matrices may be readily cut in the plates and require no finishing after the milling operation, being smooth enough from that operation alone to permit easy sliding of the matrices.

30 The use of such an aluminum alloy for the main parts of the magazine, viz, the top and bottom side plates, results in a very material reduction in the weight of the magazine structure, due to the comparatively light weight of aluminum in contrast with other metals, such as brass and steel.

In order to impart the necessary strength and stiffness to the magazine structure as a whole notwithstanding the use of the lighter metal for the upper and lower plates, the side bars 3 and the cross bars 5, 6, 7, 8 and 9 on the underside of the bottom plate 2 (and if desired the longitudinal bar 11 as well) are made of steel, and to prevent any electrolytic action which might result from the contact of steel with aluminum, it is proposed before assemblage to coat these steel parts with an aluminum paint or to subject them to the well known Parkerizing process, either process being effective for the purpose.

Having thus described my invention, what I claim is:

1. A matrix magazine comprising a pair of side plates formed of an alloy of aluminum and grooved in their adjacent faces to form guiding channels for the matrices, and side bars fastened between and spacing said plates and formed of steel.

2. A matrix magazine including a pair of side plates formed of an alloy of aluminum and grooved in their adjacent faces to form guiding channels for the matrices, and cross bars of steel fastened to the outer face of one of the side plates.

65 3. A matrix magazine including a pair of

side plates formed of an alloy of aluminum and grooved in their adjacent faces to form guiding channels for the matrices, said alloy possessing sufficient stiffness to prevent distortion and sufficient hardness to resist 70 wear from the matrices, and being free from the formation of foreign substances in the frictional engagement of the matrices therewith.

4. A matrix magazine including a pair of 75 side plates formed of an alloy consisting of aluminum, magnesium, manganese, silicon and copper, said plates being grooved in their adjacent faces to constitute guiding channels for the matrices.

5. A matrix magazine including a pair of 80 side plates formed of an alloy consisting of aluminum, magnesium, manganese, silicon and copper in substantially the proportions specified, said plates being grooved in their adjacent faces to constitute guiding channels 85 for the matrices.

6. A matrix magazine including a pair of 90 side plates formed of an alloy consisting of 94.4% of aluminum, .6% of magnesium, .5% of manganese, .5% of silicon and 4% of copper, said plates being grooved in their adjacent faces to form guiding channels for the matrices.

7. A matrix magazine according to claim 95 2, characterized by the fact that the steel bar or bars therein referred to are treated before assemblage to prevent electrolytic action between them and the aluminum side plates.

8. A matrix magazine according to claim 100 2, characterized by the fact that the steel bar or bars therein referred to are treated before assemblage to prevent electrolytic action between them and the aluminum side 105 plates.

In testimony whereof, this specification has been duly signed by:

CERTIFICATE OF CORRECTION.

Patent No. 1,906,992.

May 2, 1933.

RICHARD R. MEAD.

It is hereby certified that error appears in the printed specification of the above numbered patent requiring correction as follows: Page 2, line 96, claim 7, for the number "2" read "1"; and that the said Letters Patent should be read with this correction therein that the same may conform to the record of the case in the Patent Office.

Signed and sealed this 30th day of May, A. D. 1933.

M. J. Moore.
